RICHARD STRESAU, OF WAUWATOSA, WISCONSIN, ASSIGNOR TO A. O. SMITH CORPORATION, OF MILWAUKEE, WISCONSIN, A CORPORATION OF NEW YORK

METHOD OF ANNEALING VESSELS

Application filed September 18, 1930. Serial No. 482,657.

This invention relates to a method of annealing vessels. In the manufacture of metal vessels and particularly welded vessels it becomes desirable to heat the completed structure to a temperature capable of relieving any local stresses that may be present therein. It has been found difficult, particularly in vessels of relatively thin wall, to use a temperature high enough to accomplish the desired stress relief, within a commercially desirable length of time, without causing distortion and sagging of the walls of the vessel. It has been found additionally difficult to heat to a sufficiently high temperature to accomplish the result sought in a metal softening anneal without experiencing such distortion.

An object of this invention is to provide a method of annealing a metal vessel which will permit the use of a desirable stress relieving temperature and prevent detrimental distortion of the vessel during the application of this temperature.

Another object of this invention is to provide a method of correcting local irregularities of shape in metal pressure vessels, thereby allowing their use, under operating conditions, substantially free from points of detrimental local stress intensification.

The proper removal of shape irregularities is important in vessels subject, in use, to either internal pressure, vacuum or external pressure. The term "pressure vessel" in this specification is therefore intended to mean a vessel intended to operate under any of these conditions.

In its broader aspect, therefore, the invention resides in a method of annealing pressure vessels while obtaining the shape thereof which is correct for subsequent use under working conditions.

Other aspects of the invention will be pointed out hereinafter with reference to the accompanying drawings in which:

Figure 1 is a side elevation of a simple cylindrical vessel with elliptical heads.

Fig. 2 is an end elevation of the vessel shown in Fig. 1.

Fig. 3 is an enlarged section through Fig. 1

on line 3—3 and illustrates the action of certain forces tending to distort the vessel.

Fig. 4 is a section similar to Fig. 3 after the temperature has lowered the strength of the metal sufficiently to permit the distortion of the bottom.

Fig. 5 is a view similar to Fig. 3 showing bottom supports so placed as to assist in preventing distortion.

Fig. 6 is an enlarged view of the welded joint in Fig. 3.

Fig. 7 is a section of a thin walled vessel showing a modified form of support.

Fig. 8 is a section of a vessel to be heat treated suspended by supports attached to the top of its shell.

In the drawings, 1 is a simple cylindrical vessel, 2, 3, 4 and 5 are circumferential welds made in the construction of the vessel, 6 and 7 are longitudinal welds, 8 is a manway opening in the vessel, 9 is a reinforcing plate used to sustain the vessel wall at the manway against local distortion due to internal pressures, while in use, and 10 is a manway cover secured to the manway and suitable to sustain internal pressure.

In the practice of this invention, an annealing heat treatment is applied to the fabricated vessel in which the vessel is subjected to internal pressure to assist in the prevention and elimination of irregularities therein.

The use of the term "internal pressure" in its various modified forms refers to subjecting the inner wall of the vessel to a fluid pressure which is greater per unit area than the pressure to which the outside of the vessel is subjected. This internal pressure insures a tensioning of the walls of the vessel during its application.

If the vessel shell were thin enough to be practically without stiffness or were perfectly flexible, then the bottom thereof would assume a flat position as 11 between planes 12—12', Fig. 4. When 11 is straight, the forces 13 due to internal pressure must be transmitted undiminished through 11 to its support. The length of the straight portion 11 will then be such that when multiplied by the unit pressure inside the vessel, the

product will not be greater than the total weight of the vessel and fluid being supported on the surface under 11. When a gas of negligible weight is used, we can say PL_1 is 5 equal to or less than W , in which P = pressure per unit area applied internally, L_1 = flat portion 11 and W = total weight of vessel per unit of length. Any stiffness of the shell giving resistance against deflection may decrease the flat horizontal distance L_1 .
10

Examining Fig. 4, it will be noted that the internal pressure at flat portion 11 is sustained by the external supporting surface so that there is an unbalanced vertical force in 15 the vessel. This acts on the inside top of the vessel and is effective in helping to support the weight of the shell.

The fact that the shell has this effective support at the top explains why, with very 20 moderate internal pressures, a very nearly true circumferential shape can be maintained without external confinement of the vessel during the annealing operation.

It is desirable to use a curved support at the 25 bottom as shown at 14-14' in Figs. 1, 2 and 5.

The total width of this curved support in thin vessels preferably should be equal to or greater than L_1 as determined by $PL_1 = W$ above or
30

$$L_1 = \frac{W}{P}.$$

A supported curved surface of a shell will 35 act very similar to the flat surface 11 as in Fig. 4 if the outer edges of the curved support engage the vessel and confine the portion in contact.

P , the internal pressure, preferably should 40 not produce a fiber stress greater than the yield value of the metal at the annealing temperature thereby avoiding any material permanent enlargement of the vessel being treated. If f = fiber stress at this yield point, then $2fd = P \times D$ where D = diameter of vessel 45 in inches and d = the thickness of the shell in inches.

$$P = \frac{2fd}{D}$$

50 and

$$L_1 = \frac{W}{2fd/D} = \frac{DW}{2fd}$$

W is the weight of vessel per unit length, 55 and it is equal to $\pi D d w$, in which w = the weight of a cubic inch of the material in pounds, then

$$L_1 = \frac{D \pi D d w}{2df} = \frac{\pi w D^2}{2f}$$

The foregoing is true for very flexible walls and is a guide for the selection of supports to minimize deflections. However, the stiffness of vessel walls effects the total deflections.
60

In Fig. 3, the vessel is represented as resting on a longitudinal line at position 15, it being assumed that the vessel at the temperature existing has sufficient stiffness to make this possible. Consider the portion 16 of 70 shell 1 as a beam between the two vertical planes 17 and 17'. The weight of the remainder of the shell 1 rests upon this beam 16 at its outer extremities at 18 and 18'.

Lines 19 and 19' represent this weight and 75 line 20 represents the force applied to support the vessel at line 15. The moment of bending on this beam is the

$$\frac{WL}{4} \quad 80$$

where force 20 is W or the weight of the vessel per unit of length and distance 21 is L . This moment of bending is a fixed amount if the entire weight of this portion of the vessel is left free to rest on points 18-18'
85

M is equal to

$$\frac{FI}{y} \quad 90$$

page 562, Civil Eng. Handbook by Frye 1913, in which F = outer or greatest fiber stress, y = distance from center of the plate to the extreme fiber, I = the moment of inertia of 95 the section.

$$y = \frac{d}{2}$$

where d = thickness of plate. Page 525, Frye, 100

$$I = \frac{bd^3}{3}.$$

b = unit width of sheet (one), and then

$$I = \frac{d^3}{3}. \quad 105$$

Substituting in above

$$M = \frac{Fd^3 \times 2}{3 \times d} = 2/3 Fd^2 \quad 110$$

and

$$F = \frac{3}{2} \frac{M}{d^2}.$$

If all dimensions of the vessel should remain the same except the shell thickness, M would change directly as d , because
115

$$M = \frac{WL}{4} \quad 120$$

in which W changes proportionally to d , thereby making F the extreme fiber stress vary inversely as the thickness of the plate. The above simple illustration is used to show that as the yield point is reached by raising the temperature, the thinner shells tend to yield earlier under their own weight than the thicker ones.
125

It has been suggested to support the weight of the upper part of the vessel by struts
130

placed in a vertical position within the vessel, thereby relieving the points 18-18' of at least a portion of the weight of the vessel. This method would not be very satisfactory 5 because it gives points of concentrated force which are detrimental to the vessel.

By applying internal pressure to the vessel during heating there are, in addition to the gravity forces 19 and 19' acting on the ends 10 of the beam 16, tangential forces 22 and 22'. These forces are in a direction inclined upward, thereby assisting to prevent downward deflection of the beam. These forces, however, may not be fully effective since 15 there are radial forces, not shown, acting downward on beam 16, tending to depress it.

In Fig. 6 is shown an enlarged section through horizontal weld 6. This is shown as having been formed with an angle between 20 the plate ends different than that of the average curvature 23. The tension forces in this sheet set up by internal pressure applied during annealing will tend to cause the sheet to take the average curvature position and exert an excess of tension at the region 24.

By applying an internal pressure large enough to approach the yield point of the heated shell, the point 24 can be made to yield under tension because it receives a tension greater than the average. It will be seen that in this way, local irregularities may be permanently corrected without expanding the other portions of the shell. The same 35 can be shown with regard to irregularities due to circumferential seams or other causes.

In very thin walled vessels slight irregularities in the supports may cause indentations during the heating period. It has been found desirable in such cases to gain the advantage of the curved support shown in Fig. 40 5 as well as a yielding distributed application of such support to prevent local deformations of the vessel. This has been accomplished by the application of bands 25 extending under the vessel and secured above as illustrated in Fig. 7. The bands 25 are secured to bolts 26 and 26' which are secured to beams 27 by nuts 28 and 28'. Internal 45 pressure is introduced into this vessel by a connection similar to that of Fig. 1.

Certain types of cylindrical vessels are adapted to be suspended from lugs or fittings secured along one side of the cylindrical shell as indicated by a section shown in 55 Fig. 8. Lugs 29-29' are secured by welding or other means to the vessel along one side. These are secured by bolts 30 and 30' and nuts 31 and 31' to beams 32. Internal pressure 60 is applied through a connection similar to that shown in Fig. 1.

Without internal pressure, sagging, due to the lowering of the strength of the vessel shell by the application of heat during annealing, would cause the vertical diameter 33

to become greater than the horizon diameter 34.

Upon the application of internal pressure to the vessel, the unit pressure being the same in all directions, the total horizontal pressure on the larger diameter 33 would be greater than that on diameter 34. The difference of these total pressures would be available to swing the shell sides outwardly 70 rotating them about the supporting points 29-29' as fulcrums and thereby lifting them back toward the truly circular form. This modification operates on the principal of unequal diameters. However, this difference 75 can in practice be reduced to values that are entirely within the requirements usually set upon such vessels.

If the lugs 29-29' indicated are well distributed or are welded frequently over an extended area in such a way as to avoid serious local stress due to the weight of the vessel, there is considerable advantage in thus supporting thin vessels for annealing. The upper surface is then substantially retained 80 in true shape and the lower one has a tendency to depend in a naturally nearly true shape. The addition of internal pressure then makes it entirely practicable to maintain a proper shape during the time that a weakening of the vessel wall occurs due to raised 85 temperature. The above method applies equally well to a spherical shape.

It will be appreciated that when a given internal pressure has been predetermined from the above factors it is important to maintain this pressure accurately. The procedure of operation may be as follows: The sealed vessel is placed in position in the heating chamber and properly supported. An air control connection 35 is preferably attached to the manway cover 10 of the vessel and communicates with the interior of the vessel. This connection may consist of a pipe with a valve having a port communicating with the atmosphere. This pipe may also be connected with a source of air pressure by another valve. A pressure gauge is provided to indicate the internal pressure.

The vessel is initially full of air at atmospheric pressure, and as the temperature of the vessel is raised this air expands and the pressure in the vessel increases above the initial atmospheric pressure. When the desired predetermined pressure is reached, the valve connecting the pipe to the atmosphere is opened occasionally to expel enough air to limit the pressure to the desired value until the final temperature is reached.

In place of starting with atmospheric pressure, the valve connecting with the source of air pressure may have been opened long enough to obtain the predetermined pressure initially.

The proper annealing time is allowed, then the vessel is cooled. The pressure is main-

tained by the admission of air frequently in desired amounts from the source of air pressure until the proper metal strength is regained by the cooling of the metal. It is 5 desirable to have a very careful and accurate control of pressure during both the rise and fall of temperature. For this purpose, pressure diaphragm actuated relays have been supplied to control the opening and closing 10 of the two valves described above, thereby providing a very sensitive control of the pressure.

The predetermined pressure for supporting the walls of the vessel is usually much 15 lower than that necessary to equalize the irregularities in the walls. However, irregularities in the vessel wall may be equalized after the full stress relieving temperature is reached by manually opening the pressure 20 valve and running the gauge indication up to the predetermined amount just under the amount necessary to reach the yield point of that portion of the shell material which has the predetermined desired shape, maintaining 25 this pressure for a short time, and then lowering the same by opening the valve to the atmosphere until the shell supporting pressure is reached. The latter pressure is then maintained as before.

30 It is also possible to apply the supporting pressure only during the cooling period of the treatment, the vessel being first heated to the maximum temperature or nearly so and pressure being then applied to correct any irregularities in shape and to maintain the required 35 shape of the vessel during the cooling period in which the metal regains its strength.

For the purposes of this invention, the expression referring to the application of 40 internal pressure "during the period of elevated temperature" is intended to mean that the pressure may be applied either during the entire or only a portion of the period of elevated temperature.

45 While the drawings and descriptions have been with reference to cylindrical vessels, the use of internal pressure to support structures during annealing may be applied to various shapes of vessels.

50 I claim:

1. The method of treating a fabricated pressure vessel to relieve accumulated stresses and correct imperfections of the stress receiving shape, which comprises sealing said 55 vessel for receiving internal fluid pressure, heating the vessel to a temperature sufficient to effect the desired stress relief, maintaining an internal fluid pressure of a predetermined amount sufficient to support the weight 60 of the walls against deformation during the period of elevated temperature, raising the pressure for a limited time to a value sufficient to impose upon the walls of the vessel a fiber stress near the yield point of the material, and allowing the vessel to cool while

70 maintaining a wall supporting internal pressure.

2. The method of annealing a fabricated vessel which comprises heating the vessel to a temperature sufficient to effect a desired stress relief, maintaining during the period of elevated temperature an internal fluid pressure in excess of a predetermined amount sufficient to support the weight of the walls 75 against harmful deformation, and less than an amount sufficient to impose upon the walls of the vessel a stress equal to the yield point value of the metal, maintaining said internal pressure near the higher value for a portion 80 of the time of elevated temperature to correct local irregularities of shape, and then allowing the vessel to cool.

3. The method of relieving the stresses in a fabricated cylindrical vessel which comprises heating the unconfined vessel to a stress relieving temperature, and applying an internal fluid pressure to the vessel during the period of elevated temperature while supporting said vessel at circumferentially 85 distributed points some of which lie in longitudinal lines laterally spaced a distance 90 equal to or greater than

$$\frac{\pi WD^2}{2f}$$

95 inches, W being equal to the weight of one cubic inch of the material of the vessel, D being equal to the internal diameter of the vessel in inches and f being equal to the pounds per square inch in stress at the yield point of the material for the highest temperature employed.

100 4. The method of relieving the fabrication stresses in a cylindrical metal vessel which comprises resting said vessel upon supports contacting their surfaces laterally over a portion of the circumference, heating the vessel to a stress relieving temperature 105 and applying an internal fluid pressure to the vessel during the part of the period of elevated temperature in which the yield point of the metal of the vessel walls is effectively 110 reduced.

115 5. The method of relieving the stresses in a cylindrical metal vessel which comprises resting the vessel in a suspended flexible band support, heating the vessel to a stress relieving temperature, and applying an internal fluid pressure to the vessel during at least a portion of the period of elevated temperature.

120 6. The method of relieving the stresses in a metal vessel which comprises resting the vessel in a suspended metal band support, heating the vessel to a stress relieving temperature, and applying an internal fluid pressure to the vessel during a portion of the period 125 of elevated temperature.

7. The method of relieving the stresses in a cylindrical metal vessel which comprises suspending the vessel horizontally by means of laterally spaced lugs attached to the upper 5 surface thereof, heating the vessel to a stress relieving temperature, and maintaining an internal pressure during at least a part of the period of elevated temperature.

8. The method of relieving the stresses 10 in a metal vessel which comprises suspending the vessel horizontally by means of laterally spaced lugs attached to the upper surface thereof, heating the vessel to a stress relieving temperature, and maintaining an 15 internal fluid pressure during a part of the period of elevated temperature.

9. The method of supporting a fabricated 20 pressure vessel during the process of annealing, which comprises supplying an internal fluid pressure to the vessel, and heating the vessel to an annealing temperature to release internal stresses locked in the metal walls of the vessel, the internal pressure supplied being sufficient to support the vessel 25 when heated to maintain the fabricated shape.

10. The method of supporting a fabricated 30 pressure vessel during the process of annealing, which comprises supplying an internal fluid pressure to the vessel, heating the vessel to an annealing temperature to release stresses locked in the vessel wall, and controlling the internal pressure to compensate for changes in temperature to maintain the 35 vessel in its fabricated shape.

11. The method of supporting a fabricated 40 vessel during the process of annealing, which comprises supplying an internal fluid pressure to the vessel, heating the vessel to an annealing temperature to release stresses locked in the wall of the vessel, maintaining the internal pressure at a value sufficient to support the wall when heated, and raising the pressure to remove irregularities formed 45 in the vessel during the process of fabrication.

12. In the method of fabricating pressure 50 vessels, the step of welding plates to erect a vessel of the desired shape, applying an internal fluid pressure to the vessel, heating the vessel to an annealing temperature to release stresses locked in the wall of the vessel during the welding of the plates, and maintaining the internal pressure supplied to the 55 vessel at the proper value to support the heated walls, and allowing the vessel to cool while still subjected to pressure.

13. In the method of fabricating pressure 60 vessels, the step of welding plates together to erect a vessel of the desired shape, applying internal fluid pressure to support the vessel wall, heating the vessel to annealing temperature to release stresses locked in the vessel wall, maintaining the internal fluid 65 pressure in the vessel after it is heated, and

raising the internal pressure to a predetermined value to remove irregularities that may be in the vessel after fabrication.

14. The method of supporting the walls of 7 a fabricated pressure vessel during the process of annealing which comprises heating the vessel to an annealing temperature to release stresses in the metal walls, and supplying and maintaining in the vessel a fluid pressure sufficient to support the metal wall 75 when it reaches a temperature at which it cannot support its own weight.

In witness whereof I have signed my name at Milwaukee, Wisconsin, this 13th day of September, 1930. 80

RICHARD STRESAU.
